TRANSLUCENT BUILDING BLOCK OR THE LIKE

Donald J. Behnk, Allison Park, Pa., and Wesley E. Lerdon, Houston, Tex., assignors to Pittsburgh Corning Corporation, Pittsburgh, Pa., a corporation of Pennsylvania

Filed Apr. 19, 1967, Ser. No. 6,756

Term of patent 14 years

(Cl. D18—2)

We claim:

The ornamental design for the translucent building block or the like, substantially as shown and described.
